UNITED STATES PATENT OFFICE.

RICHARD H. RAGLAND, OF ST. LOUIS, MISSOURI, ASSIGNOR OF ONE-HALF TO FRANK HAGGENJOS, OF ST. LOUIS, MISSOURI.

IMPLEMENT-HANGER.

1,314,981.

Specification of Letters Patent.

Patented Sept. 2, 1919.

Application filed August 30, 1917. Serial No. 188,935.

To all whom it may concern:

Be it known that I, RICHARD H. RAGLAND, a citizen of the United States, and resident of St. Louis, Missouri, have invented certain new and useful Improvements in Implement-Hangers, of which the following is a specification.

This invention relates to improvements in implement-hangers, and has for its object 10 a base plate provided with a swivelly mounted hanger in which may be seated or hung tools of different structure.

A further object is to provide a device which may be secured to a wall or the back 15 of a work-table or similar device upon which implements may be hung.

Figure 1, is a front view of my device showing the hanger or holder which is used for implements with a straight handle in 20 its downward position.

Fig. 2, is a vertical sectional view taken on the line 2—2 of Fig. 1, showing a straight handle locked within my device, also showing it in un-locked and idle positions by 25 dotted lines.

Fig. 3, is a perspective view of the hanger when made use of for awls, screw-drivers or the like.

In carrying out my device I provide a 30 base plate or bracket 5, provided with a slot 6; intermediate with the ends I provide a bulged or outwardly curved portion 7 which is to receive the rod 8 and around this rod is fastened or secured my hanger 9. When 35 the device is intended to be used to support a straight handle such as is provided with brooms, mops, rakes or the like, I provide a ring 10, its inner surface 11, being punched out so as to leave the edges 12 on its top surface and 13 on the lower surface sharp. As 40 is seen in Fig. 2, the edge 12 on the upper surface and the edge 13 on the lower surface grip or bite into the handle and prevent it from slipping and thereby cause the implement 45 to lose its shape or form.

When it is desired to use the implement to hold objects such as awls, ice-picks or any other device I use the form shown in Fig. 3, which device is provided with a shoulder 14, and a horizontal portion 15. The 50 shoulder 14 is intended to rest against the bracket 5, and the horizontal portion 15 is provided with a bore 16, through which the implement is placed. At the same time keeping the cutting edge or point away from 55 the wall.

By the construction of my device I eliminate the possibility of implements which have a straight handle from slipping down and distorting the ends thereof as is especially common in the mop and broom 60 hangers of present construction, where a spring holder is made use of.

Another feature is that when my device as shown in Figs. 1 and 2 is out of operation 65 its parts will be out of the way and not extending from the wall unless used on the bench or for hanging such implements as awls, screw-drivers, wrenches or shovels or the like. 70

Having fully described my invention what I claim is:

An implement hanger having an elongated base plate of sheet metal provided with a central elongated slot, the walls of the base 75 plate formed into a loop, a bracket of sheet metal having a circular opening, the one end of the bracket provided with trunnions which fit into the loops of the sheet metal base plate, said bracket being adapted to 80 bind the handle of an implement, substantially as specified.

In testimony whereof, I have signed my name to this specification, in presence of two subscribing witnesses.

RICHARD H. RAGLAND.

Witnesses:

B. M. ANSTINE,
WALTER C. STEIN.
